UNITED STATES PATENT OFFICE.

CHARLES A. LINDBERG, OF STURGIS, MICHIGAN, ASSIGNEE TO STURGIS STEEL GO-CART COMPANY, OF STURGIS, MICHIGAN.

ADJUSTABLE SUPPORT.

Application filed June 24, 1921. Serial No. 480,105.

To all whom it may concern:

Be it known that I, CHARLES A. LINDBERG, a citizen of the United States, residing at Sturgis, county of Saint Joseph, and State of Michigan, have invented certain new and useful Improvements in Adjustable Supports, of which the following is a specification.

This invention relates to improvements in adjustable supports.

The main objects of my invention are:

First, to provide an improved adjustable support for carriage tops or hoods of children's carriages and the like which is very easily operated and at the same time is very secure.

Second, to provide an improved adjustable support for carriage tops and the like in which the parts are very simple and economical to produce and are easily assembled.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which;

Fig. I is a detail side elevation of a structure embodying the features of my invention as applied to a child's carriage, the side bar only of the carriage being shown.

Fig. II is an enlarged detail section on a line corresponding to line 2—2 of Figs. I, III and IV.

Fig. III is a vertical section on a line corresponding to line 3—3 of Figs. I, II and IV.

Fig. IV is a detail inside elevation of the support removed from the carriage.

In the drawing similar reference characters refer to similar parts throughout the several views, and the sectional views are taken looking in the direction of the little arrows at the ends of the section lines.

Referring to the drawing, 1 represents the side bar of the body of a child's carriage. The body member or supporting plate 2 is provided with rearwardly offset clips 3 adapted to receive the attaching screws 4.

A reinforcing plate 5 is provided for the bar 1. The bracket member 6 is forked at 7

to facilitate the attachment of the top thereto.

The bracket member is pivotally supported on the supporting plate by means of the tubular pivot 8. The supporting plate 20 has a hole 9 therein, while the bracket member has a series of holes 10 adapted to be brought into register with the hole 9 as the bracket member is swung on its pivot.

A stud 11 is arranged through the pivot 8 65 to project at the inner side of the supporting plate. A lever-like locking dog 12 is loosely engaged on this stud and is provided with a lug 13 at its inner end engaging the hole 14 in the supporting plate, so that the 70 dog is supported for swinging movement.

The dog is provided with a pin 15 adapted to engage the aligned holes in the bracket member and the supporting plate thereby locking the bracket member in its adjusted 75 position. The dog is provided with a finger-piece 16 projecting below the supporting bracket. The dog is yieldingly held in engagement by means of the spirally coiled spring 17 arranged on the stud. The stud 80 is notched at 18 to receive the U-shaped retaining clip 19 which is engaged in the notches and its ends forced together, thereby retaining it in position.

My improved adjustable support is especially designed by me for use on light children's carriages and on toy or doll carriages, it being very economical to produce, light in weight, and at the same time easily operated, and is also strong and durable. 90

Having thus described my invention, what I claim as new and desire to secure by Letters Patent, is:—

1. In a structure of the class described, the combination of a supporting plate, a bracket member, a tubular pivot for said bracket member carried by said supporting plate, said supporting plate being provided with a hole at one side of its pivot and said bracket member being provided with a series of holes adapted to be brought into register therewith, a stud having notches in its inner end disposed through said pivot to project at the inner side of said supporting plate, a dog loosely engaged on said stud 105 and provided with a pin adapted to engage registering holes in said supporting plate and bracket member and having a finger piece at its outer end and a lug at its inner end, said supporting plate having an opening 110

therein adapted to receive said lug, a spirally coiled spring arranged on the inner end of said stud to act on said dog, and a U-shaped spring retaining clip engaging said notches in said stud.

2. In a structure of the class described, the combination of a supporting plate, a bracket member, a tubular pivot for said bracket member carried by said supporting plate, 10 said supporting plate being provided with a hole at one side of its pivot and said bracket member being provided with a series of holes adapted to be brought into register therewith, a stud disposed through said pivot to 15 project at the inner side of said supporting plate, a dog loosely engaged on said stud and provided with a pin adapted to engage registering holes in said supporting plate and bracket member and having a finger 20 piece at its outer end and a lug at its inner end, said supporting plate having an opening therein adapted to receive said lug, and a coiled spring arranged on the inner end of said stud to act on said dog.

25 3. In a structure of the class described, the combination of a supporting plate, a bracket member pivotally mounted thereon, said supporting plate being provided with a hole at one side of its pivot and said bracket 30 member being provided with a series of holes adapted to be brought into register therewith, a stud having notches in its inner end projecting at the inner side of said supporting plate, a dog loosely engaged on said stud 35 and provided with a pin adapted to engage registering holes in said supporting plate and bracket member and having a lug at its inner end, said supporting plate having an opening therein adapted to receive said lug, 40 a coiled spring arranged on the inner end of said stud to act on said dog, and a U-shaped spring retaining clip engaging said notches in said stud.

4. In a structure of the class described, the 45 combination of a supporting plate, a bracket member pivotally mounted thereon, said supporting plate being provided with a hole at one side of its pivot and said bracket member being provided with a series of holes 50 adapted to be brought into register therewith, a stud projecting at the inner side of said supporting plate, a dog loosely engaged on said stud and provided with a pin adapted to engage registering holes in said supporting 55 plate and bracket member and having a lug at its inner end, said supporting plate having an opening therein adapted to

receive said lug, and a coiled spring arranged on the inner end of said stud to act on said dog.

5. In a structure of the class described, the combination of a supporting plate, a bracket member, a tubular pivot for said bracket member carried by said supporting plate, a stud disposed through said pivot to 60 project at the inner side of said supporting plate, a locking dog for said bracket member loosely engaged on said stud with its inner end engaged with said plate for tilting adjustment, a coiled spring arranged on the 65 inner end of said stud to act on said dog, and a spring retaining clip engaged on said stud.

6. In a structure of the class described, the combination of a supporting plate, a bracket member pivotally mounted on said supporting plate, a stud projecting inwardly from said supporting plate, a lever-like locking dog loosely engaged on said stud and having its inner end engaged with said plate so that it is supported for swinging movement, the 70 swinging end of the said dog being provided with a pin engaging said bracket member through said supporting plate, and a spring arranged on said stud to act on said dog.

7. In a structure of the class described, the combination of a supporting plate, a bracket member pivotally mounted on said supporting plate, a stud projecting inwardly from said supporting plate, a lever-like dog loosely 75 engaged on said stud and having its inner end engaged with said plate so that it is supported for swinging movement, the swinging end of the said dog being provided with a pin engaging said bracket member through 80 said supporting plate, and a spring arranged on said stud to act on said dog.

8. In a structure of the class described, the combination of a supporting plate, a bracket member pivotally mounted on said supporting plate, 85 a stud projecting inwardly from said supporting plate, a lever-like locking dog for said bracket member engaged on said stud and having its inner end engaged with said plate so that it is supported for swinging 90 movement, and a spring arranged on said stud to act on said dog.

In witness whereof, I have hereunto set my hand and seal in the presence of two witnesses.

CHARLES A. LINDBERG. [L.S.]
